UNITED STATES PATENT OFFICE.

JOSEPH LIMONCELLO, OF CHICAGO, ILLINOIS.

DRUM.

1,349,840.

Specification of Letters Patent. Patented Aug. 17, 1920.

Application filed January 14, 1920. Serial No. 351,300.

To all whom it may concern:

Be it known that I, JOSEPH LIMONCELLO, a citizen of the United States, residing at Chicago, in the county of Cook and State 5 of Illinois, have invented certain new and useful Improvements in Drums, of which the following is a specification.

This invention relates to drums or cylindrical containers.

10 One of the objects of the invention is to decrease the cost of construction and to increase the desirable qualities of devices of this character.

Another object is to provide a substantially damp proof drum for coffee, or the like, by lining it with a moisture resisting sheet of material, such as calendered paper, or card board.

20 Another object is to improve the head and chime structure; to cheapen the cost of production; to render the head more convenient for placement and replacement, and more durable.

Other, further and more particular objects of the invention will become readily apparent, to persons skilled in the art, from a consideration of the following description when taken in conjunction with the drawings, wherein:—

30 Figure 1 is a top plan view of the preferred form of drum with the head in place in the drum.

Fig. 2 is a central, vertical section through the drum and head.

35 Fig. 3 is a similar view of the drum and head.

Fig. 4 is a top plan view of a modified form of the head in place, in the drum.

40 Fig. 5 is a central, vertical section through the drum.

Fig. 6 is a fragment of the elevation of the drum.

In all the views the same reference characters are employed to indicate similar 45 parts.

I have found that by placing the hoops of the drum in pairs, one hoop inside and another hoop outside in the same horizontal plane, at the ends of the drum and intermediate thereof, that the structure is rendered much stronger and that the cylindrical walls of the structure may be made consequently relatively thinner. I have also discovered that a moisture proof lining, 55 lying next to the outside wall or covering

constituting the main portion of the cylinder, and between it and the respective pairs of hoops, not only contributes to the moisture resisting qualities but adds considerably to the strength of the structure. I have 60 also found that by placing the cleats on the heads of the drum in proper relation, that much thinner material may be used for the heads with equal strength than has heretofore been customary.

65 10 represents a wood veneer with its grain running axially with the cylinder and terminating at the salient edges of the chimes of the drum. Hoops 11, 12, 13 and 14 are placed on the outside of the drum, the terminal hoops 11 and 14, being somewhat wider than the intermediate hoops 12 and 13. Hoops 11', 12', 13' and 14' are placed on the inside of the cylinder and constitute the pairs of hoops to be used in the structure. 70 A lining 15, preferably of moisture resisting paper, or the like, such as calendered board or paper is placed preferably in intimate contact with the cylinder wall 12 and between the respective pairs of hoops. The 75 paper lining terminates inside of the chimes as at 16 as a means for indicating the position of the heads 17 and 18.

80 In Fig. 1, I have shown a cleat 19 extending across the body part 20 of the head 85 and across the grain thereof. Shorter cleat members 21 and 22 are placed at right angles between the cleat member 19 and the other extremes of the head. The cleats are shorter than the distance between the interior surfaces of the cylinder 10 and shorter than the diameter of the head 20 to include 90 a hoop 23. The disk 20 of the head 17 shows the cleats 19, 21 and 22 on one side, whereas the head 18, in the bottom of the drum, shows the cleats 19' and 21' on opposite sides of the head in which instance the cleats each extend to the dimensions of the head as described with reference to the head 17.

100 To place the head in position inside of the drum and secured therein, the head is entered in the end of the drum until the inner surface is in contact with the upper surface of the paper lining, as at 16. At 105 this time there is considerable space between the end of the cleat and the chime of the drum. Now when the head is in place in the drum, the hoop 11' is placed between the drum and the cleat ends and nails are 110

then driven through the hoop 11—11' and through the outer wall 10 into the ends of the respective cleats, as clearly shown in Fig. 2. By this means the head of the drum 5 is easily placed in position and the hoop 11' is just as easily put in its position, after insertion of the head, and when it is desired to remove the head, 17 or 18, as the case may be, the nails are removed, where- 10 upon the hoops 11' or 14' may be easily taken from their positions and the head will be as easily displaced. By this means the head may be placed in position and displaced without mutilating any of the parts 15 of the structure.

In Fig. 4 a single cleat 26 is shown in which event the thicker body portion 27 of the head is required. In Fig. 3 I have shown the paper lining inside of the hoops 20 12' and 13' instead of being located between the hoops. This leaves a smoother interior of the drum, but the structure is not quite so strong as the preferred form shown in Fig. 2.

25 In either of the structures nails are passed through the pairs of hoops and through the outer walls and lining and are preferably clenched on the inside of the drum. This makes a superior means of support and 30 provides a very durable and strong wall with a minimum thickness of material composing the wall.

The outside cleats, attached to the respective heads, are in the same horizontal 35 plane with the ends of the cylindrical walls therefore supporting the contents of the

drum when the latter is standing on either of its ends.

Having described my invention what I claim as new and desire to secure by Letters Patent is:—

A drum having an outside, one-piece wall, of veneer, with the grain extending axially of the drum; a lining of calendered paper in intimate contact with the entire inner 45 surface of the outer wall and terminating inside the chime at each end; a plurality of pairs of hoops, between the usual end hoops, one of each pair on the inside of the structure and one on the outside thereof; a head 50 in each end, each head neatly corresponding in diameter to the inner diameter of the outer wall; a cleat on the inner surface of the head, equal in length to the diameter of the head; another cleat on the outer surface of the head, disposed at right angles to the inner cleat, said outer cleat being materially shorter than the diameter of the head, at each end, and secured to the head before the head is placed in position in the 60 end of the drum; a hoop, insertible between the inner surface of the outer wall and the ends of the outer cleat, after the head has been placed in the end of the drum and means to secure the head, hoop 65 and cleat, in place whereby to provide a strong, moisture-proof drum and to facilitate closing thereof.

In testimony whereof I hereunto subscribe my name.

JOSEPH LIMONCELLO.
